RECORD AND RECORD HOLDER

Filed Feb. 20, 1925

ARTHUR A. DIONNE.

By C. J. Stockman

Attorney

UNITED STATES PATENT OFFICE

ARTHUR A. DIONNE, OF CHICAGO, ILLINOIS, ASSIGNOR TO THE ALVEY-FERGUSON COMPANY, OF CINCINNATI, OHIO, A CORPORATION OF OHIO

RECORD AND RECORD HOLDER

Application filed February 20, 1925. Serial No. 10,584.

This invention provides a record keeping means which is formed of two members, one of which constitutes a holder in which the other is slidably and removably mounted, and which slidably and removably mounted member is composed of a card, tag, ticket or sheet, (as contradistinguished from a tablet or the like) comprising a series of individually detachable coupons having appropriate indicia thereon and a body section which remains intact and which is provided with indicia corresponding to the indicia on all the coupons. More particularly set forth, the members which constitute this record keeping means are so correlated that one member—hereinafter called "holder"—will act as a holder and as a guide for the other member—hereinafter called "card" for brevity's sake—and will cause the slidable movements of said card to be stopped at a place at which a coupon is in position to be detached: and, still more particularly set forth, the card and the holder are provided with co-acting elements (as lines of weakness defining the coupons on the card and thin edges on the holder) by which detachment of the coupons is facilitated. Moreover, the correlation of the members is such that when a coupon is in position to be detached, the corresponding section of that part of the card which remains intact is exposed, and when the coupon has been detached the card may be slid longitudinally of the holder to bring the succeeding coupon into position and in said movement of the card the intact portion thereof will travel through an opening in the holder and will protrude from said holder, the protruding part of the card thereby forming an element which may be grasped to render the sliding of the card more easily accomplishable.

A record keeping means having the foregoing structural characteristics is applicable in principle to many different businesses or industries and with relation to various things of which record should be made, merely by appropriate designations on the card. Therefore, it is not the intention herein to restrict the protection to the use of the correlated card and holder in any particular business

or industry, or in relation to any particular kind of record.

My invention, however, is more especially intended for use in relation to the manufacture of articles which involve a series of operations respectively performed by different operatives or workmen and which are handled in groups by the respective operatives or workmen, instead of going singly through the shop or shops. It is especially advantageous for use in the relation just mentioned, as a means by which the records of the work of the several operatives upon the group of articles which constitute a batch may be made or kept, as a basis for the earnings of the respective operatives, or as a memorandum of the time consumed by the operatives in the performance of their particular operations on the batch, respectively, or both.

The manufacture of footwear, as shoes, on a large commercial scale presents a typical example of a most beneficial application of the principle of this invention. Indeed, it was primarily created for such use. For the foregoing reasons the invention will be particularly described with reference to its use as a means for the keeping of the records of the operatives in the manufacture of shoes on a large commercial scale, but without thereby intending to restrict the scope of the protection thereto.

Referring to the drawing:

Figure 1 is an elevation of the front of the card holder.

Fig. 2 is a transverse sectional view of the same taken on the line 2—2 of Figure 1.

Fig. 3 is a vertical sectional view of the lower portion of the holder, taken on the line 3—3 of Figure 1.

Figs. 4 and 5 are sectional views taken respectively on lines 4—4 and 5—5 of Fig. 1.

Fig. 6 is a front view of the card used with the holder, this card containing only a sufficient portion of the printed matter to enable one to understand the invention.

Fig. 7 is a fragmentary view of the assembled card and holder, and with certain of the coupons detached from the card, for the purpose of disclosure.

In the drawing, 1 designates the holder, 100

which is preferably made from sheet metal and includes a body portion 2 and a cross bar 3. The body portion has apertures 4 through which elements suitable to attach the holder to the rack, not shown, may extend, and the side edges of the body are bent inwardly to provide side grooves within side guides 5. The lower end of the body has a depending tongue 6 provided with spaced forwardly extending ledges 7, that are arranged on opposite sides of a tab 8.

The cross-bar 3 is spaced from the body, as best shown in Figs. 2, 3 and 4, to provide a slot 9, for a purpose hereinafter described. 15 The cross-bar has its ends secured to the side guides by soldering or the like, as shown at 10, and the cross-bar also has a depending tongue 11 which extends between the ledges 7 and is provided with two windows 12.

20 This card holder is designed to be placed on the receptacle (as a rack) carrying a particular lot of shoes, and when the receptacle starts on its journey, a complete card of the character shown in Fig. 6 is inserted from the 25 upper end into the guides 5. This insertion is facilitated by arranging outwardly extending tongues 13 at the upper end of the guides, as best shown in Figs. 1 and 5. When the card has been moved downwardly sufficiently it 30 will rest on the ledges 7.

Referring now more specifically to the structure of the card, it will be noted that it is provided at its upper end with indicia 14 to indicate the particular job, and with data 35 15 to designate the specific stock. The name of the factory may be placed on the card at 16, and below this will be placed other data 17 and 18, useful in keeping the records.

Below a line 19 extending transversely 20 across the card, the card is divided into columns 20 and 21, which remain intact and may be referred to as the permanent record columns for the management. These columns are divided by transverse lines into spaces 45 22, each to contain data 23 indicating a particular operation to be performed on that lot of shoes.

Arranged alongside of the columns 20 and 21 are columns 24 and 25, which may be 50 called the workman's coupon columns. The column 24 will have as many coupons 26 as there are delineated spaces 22 in the column 20, and each coupon will contain data 27 which corresponds with the data 23 on the delineated space with which it is in alignment.

Likewise, the column 25 will contain as many coupons 28 as there are spaces 22 in the column 21, and each of these last mentioned 60 coupons will have indicia 29 corresponding to the data 23 on its complementary space 22 in the column 21.

Each coupon will also contain additional data 30 and 31 to indicate a particular job 65 and a specific workman.

In the manufacture of shoes and the like there are a multiplicity of operations between and including the assembling of the uppers and lasts and the completion of the shoe. These operations, respectively, are performed at different points, called "work stations", in the shop, at each of which there is one or more operatives, the number of operatives at each depending upon the length of time required in the performance of the operation carried on thereat as compared with the time required to perform other operations entering into the construction of the shoe, the aim, of course, being to so co-ordinate the work that there will be as few interruptions as possible in the progress of the shoe from the assembling of the uppers and lasts to the finished shoes—packed and ready for shipment, if desired. The illustrated card has each of its coupons respectively designated to relate it to a particular operation and the management columns have corresponding designations of all the operations.

In practice, several pairs of uppers with lasts therein, are placed on a rack at or adjacent the station at which the lasts are placed in the uppers and these are kept together during the entire process of manufacturing the shoes. The rack with the work thereon and provided with my improved record-means is then started on its course. When it reaches the first operator who is to work on that particular lot of shoes, he, after completing his work, detaches, say the lowermost right hand coupon, by tearing along the dotted lines 32 and 33, and this operation is facilitated by the angularly disposed lower edge 34 of the cross-bar 3 and side edge 35 of the tab 11; or, in the case of the lowermost left hand coupon, by the similarly angularly disposed edges 38, 39 of the holder. The operator keeps this coupon, as his record of work performed on that particular job, etc., and before passing that lot of shoes on to the next operator, he makes a proper notation through the right hand window 12 onto the lowermost space 22 in the column 21, so that the management may determine who performed that particular work also other particular data, if any is required to be given in connection with that particular operation.

This lot of shoes then passes on to the next worker and he after completing his work detaches the lowermost coupon in the column 24 by tearing along the dotted lines 36 and 37, and he makes his entry through the left hand window 12, onto the lowermost space 22 in the column 20. This operation of tearing the coupon is of course facilitated by the edges 38 and 39 of the holder.

It will be noted that similar score lines 32 and 36 extend throughout the columns 23 and 24 and that the score lines 33 and 37 extend throughout the height of the columns,

to aid the operators in tearing off the coupons.

As the work progresses and coupons have been torn off the lower ends of both columns 24 and 25, the columns 20 and 21 will protrude correspondingly from the holder, as shown in Figure 7, and will form a tab which may be grasped by the successive operators and thereby will facilitate their operations of sliding the card upon the holder to move the succeeding coupon or pair of coupons, into position for removal.

After all of the coupons have been detached, that is, after all of the work has been completed, the record remaining will be on a substantially T-shaped sheet, and it is this sheet that goes to the person or department which has charge of the records of all the operatives. The coupons, of course, are retained by the respective operatives as their evidence of the work done by them, at least until the work has been paid for. The office record and the workmen's coupons obviously act as a check upon each other, thereby assuring accuracy in the accounts between the office and the individual operatives.

As stated heretofore, it is obvious that the card holder described and the record sheet disclosed, might be used in various businesses, by simply placing the necessary data on the card.

From the foregoing it is believed that the construction, operation and advantages of the invention may be readily understood by those skilled in the art, and it is apparent that changes may be made in the details disclosed without departing from the spirit of the invention, as expressed in the claims.

What is claimed and desired to be secured by Letters-Patent is:

1. A record-keeping means comprising a holder and a card: the holder including a body portion having spaced ledges at its lower end and guides at its sides, and also having a cross-bar extending between said guides and spaced from the body portion, said card being slidably and removably mounted on the holder and having at each side a line of consecutively arranged severable sections in positions to successively engage the corresponding ledge and also having between said lines of severable sections a portion which is movable between said spaced ledges after removal of one or more pairs of said severable sections.

2. A record-keeping means comprising a holder and a card: the holder including a body portion having a cross-bar and a tab, the tab provided with ledges spaced from the cross-bar and with windows arranged in its forward face and between the ledges, said card being slidably and removably mounted on the holder and having at each side a line of consecutively arranged severable sections in positions to successively engage the cor-

responding ledge and also having between said lines of severable sections a portion which is movable through the space between said ledges and is provided with columns, each composed of spaces which are consecutively exposed through the corresponding window.

3. A holder for slidably supporting a card having rows of consecutively arranged severable coupons disposed at opposite sides of the card and spaced from each other; said holder including a body portion having ledges at its lower end in positions to be engaged by the coupons at the corresponding sides of the card and spaced from each other to permit the portion of the card between the rows of coupons to remain intact and to be moved through said space after removal of one or more pairs of coupons, said holder also including guides for the sides of the cards and a cross-bar extending between said guides and spaced from the body part to permit the card to pass between it and the body part and also spaced from the ledges a distance corresponding to the distance between the top and bottom of each coupon.

4. A holder for slidably supporting a card having rows of consecutively arranged severable coupons disposed at opposite sides of the card and spaced from each other; said holder including a body portion having a tongue provided with ledges disposed in a spaced relation and in position to be engaged by successive coupons at corresponding sides of the card, said body part also having a cross-bar positioned to extend across the front of the card with an edge spaced from said ledges a distance corresponding to the distance between the top and bottom of each coupon, the space between the ledges corresponding to the distance between the rows of coupons, to permit the part of the card between said rows of coupons to be moved between the ledges after removal of one or more pairs of coupons, and said cross-bar having a tongue to overlie the portion of the card between the pair of coupons last removed and which tongue is provided with windows through which said portion of the card will be exposed.

5. A record-keeping means comprising a holder having means for slidably supporting a card, and having a ledge at one end of the holder for limiting the sliding movement of the card, said holder also having edges one of which is in spaced relation to the ledge to expose a section of the card to be detached, said edges facilitating detachment of said section from the card.

6. A record-keeping means comprising a holder having a pair of transversely spaced ledges at one end of the same, and having edges in angular relation adjacent each of the ledges, one of which is in spaced relation to the ledge, said holder being adapted to

support a card with end portions resting against said ledges, and said angular edges being adapted to facilitate the tearing of coupons from the card when in such position.

5 7. A record-keeping means including a holder having a window and ledges at opposite sides of the window, said holder being adapted to support a card with a portion of its face behind said window and portions of its edge resting against said ledges, said holder also having angularly disposed edges adjacent each ledge and adapted to facilitate the detachment of parts of the card bounded by the same.

10 15 8. A record-keeping means including a holder having spaced ledges and being adapted to support a record card with portions of an edge resting against said ledges, said holder having a cross bar positioned to be in front of the card and provided with windows adjacent the ledges to exhibit portions of the card, said cross bar also having spaced pairs of angular edges beyond which the card projects, said edges facilitating the tearing of coupons from the card.

20 25 9. A record-keeping means including a member comprising a body portion having spaced ledges at its lower end and guides at its sides, and a cross-bar extending between said guides and spaced from the body portion.

30 35 10. A record-keeping means including a member comprising a body portion provided at one end with spaced ledges and having guides at its side edges, and a cross bar extending between the guides, spaced from the body portion and having a window arranged adjacent said ledges.

40 45 11. A record-keeping means including a member comprising a sheet metal body portion having its side edges bent inwardly to provide oppositely disposed guides, a tab provided at one end of the body portion and having spaced ledges, and a cross-bar extending between the guides, spaced from the body portion and having a window arranged adjacent to said ledges.

50 55 12. A record-keeping means comprising a card and a holder adapted to slidably mount the card, said card including a body portion and a series of individually detachable workmen's coupons, the body portion having indicia respectively related to a series of operations to be performed and said coupons containing indicia related to particular operations, respectively; and said holder including a means arranged to be engaged by an edge of the undetached coupon immediately succeeding the coupon last detached and serving to position said undetached coupon for convenient subsequent detachment, the holder also including an opening through which said body portion of the card may progressively pass when coupons are detached.

60 65 13. A record-keeping means comprising a

card and a holder upon which the card is slidably mounted in operation, said card including an intact body portion and two series of individually detachable sections arranged respectively on opposite sides of said body portion, and said holder having means to facilitate individual detachment of said sections from the body portion and to permit sliding movement of the card on the holder as detachable sections are removed, said means including an opening through which said body portion may pass and elements on opposite sides of said openings to engage the sections to be detached, respectively.

70 75 80 In testimony whereof I affix my signature. ARTHUR A. DIONNE.
